UNITED STATES PATENT OFFICE.

JAMES THOMAS, OF CATASAUQUA, PENNSYLVANIA.

HYDRAULIC MOTOR.

SPECIFICATION forming part of Letters Patent No. 226,133, dated March 30, 1880.

Application filed September 23, 1879.

To all whom it may concern:

Be it known that I, JAMES THOMAS, of Catasauqua, in the county of Lehigh and State of Pennsylvania, have invented a new and useful Improvement in Hydraulic Motors, of which 5 the following is a specification.

The figure is a vertical section of my hydraulic ram.

The object of this invention is to furnish hydraulic rams which shall be so constructed that they may be used to deliver power.

The invention consists in the combination of a secondary piston and cylinder with the water-chamber of the ram, as hereinafter fully 15 described.

A represents the pipe through which the water is carried to the chamber B. C is the discharge-opening through which the water escapes intermittently as the valve D opens 20 and closes. The inner part of the chamber B opens into a cylinder, E, in which is the piston or plunger G.

With this construction, as the water moves inward through the pipe A and chamber B

its momentum closes the valve D and forces 25 the piston or plunger G up through the cylinder E. When the water from the inlet-pipe A has expended its momentum it comes to rest and the valve D drops and opens, and allows the water in the chamber B to flow out and 30 the piston G to drop, and piston G is again ready to be forced up by the momentum of the moving column of water upon the closing of the valve D. The power imparted to the piston G is conveyed or delivered by the rod F. 35

Having thus described my invention, I claim as new and desire to secure by Letters Patent—

The combination, in a hydraulic motor, of the chamber B, having the discharge-opening 40 C, the valve D, and the piston G, arranged as shown and described, for the purpose specified.

JAS. THOMAS.
